[57] ABSTRACT

A circuit interrupter trip device responsive to abnormal currents in conductors of an electrical distribution system characterized by a circuit breaker within a first insulating housing and having a mechanism for opening and closing separable contacts which mechanism comprises a releasable member movable from latched to unlatched positions, trip means comprising a stationary magnetic structure for each conductor as well as a coil and core assembly and armature therefor, a trip bar movable to unlatch the circuit breaker mechanism and biased in the latched positions, and a manually operable trip pin for moving the trip bar to the unlatched position.

CIRCUIT INTERRUPTER TRIP DEVICE**BACKGROUND OF THE INVENTION****Field of the Invention**

This invention pertains to a circuit interrupter and more particularly it pertains to a manually releasable pin for tripping the interrupter to the open circuit position.

CROSS-REFERENCE TO RELATED APPLICATIONS

This invention is related to that disclosed in the application of Albert E. Maier and William J. Stephenson, Jr., Ser. No. 345,394, filed Mar. 27, 1973.

DESCRIPTION OF THE PRIOR ART

Generally, circuit breakers that comprise overcurrent protective devices such as disclosed in U.S. Pat. No. 3,530,414. Circuit breakers of that type have functioned satisfactorily for responding to such abnormal currents as overcurrents, ground fault currents, and short circuits that occur in an electrical distribution system. It has been found that a more satisfactory device is obtained by providing a manually actuated pin for tripping the circuit breaker to the open circuit position.

SUMMARY OF THE INVENTION

In accordance with this invention, there is provided a protective device for a circuit interrupter which comprises a stationary magnetic structure for each conductor of an electrical distribution system and comprising a coil and core assembly and an armature, a trip bar movable to effect tripping of the circuit breaker mechanism and being biased in the latched position, a lever means associated with each stationary magnetic structure for moving the trip bar to the unlatched position, the lever means comprising the armature and being movable in response to abnormal currents in at least one of the conductors, the lever means also comprising a lever which is biased away from the core assembly, means for adjusting the spacing between the lever and the core assembly, and a manually operable member for moving the trip bar to the tripped position.

The advantage of the device of this invention is that it provides for a more efficient unit.

BRIEF DESCRIPTION OF THE DRAWINGS

FIG. 1 is a vertical sectional view of one pole of a 50 multiple circuit breaker;

FIG. 2 is a vertical sectional view taken on the line II-II of FIG. 1;

FIG. 3 is a vertical sectional view taken on the line III-III of FIG. 1;

FIG. 4 is a vertical sectional view taken on the line IV-IV of FIG. 3;

FIG. 5 is a vertical sectional view taken on the line V-V of FIG. 3; and

FIG. 6 is a plan view of the trip device shown in FIGS. 2-5.

DESCRIPTION OF THE PREFERRED EMBODIMENTS

In FIG. 1, a circuit breaker is generally indicated at 3 and it comprises an insulating housing 5 and a circuit breaker mechanism 7 supported within the housing.

The housing 5 comprises an insulating base 9 and an insulating cover 11.

The circuit breaker mechanism 7 comprises an operating mechanism 13, and a latch and trip device 15. Except for the latch and trip device, the circuit breaker 3 is of the type that is generally described in the patent to Albert R. Cellerini et al, U.S. Pat. No. 3,287,534 issued Nov. 22, 1966. The circuit breaker 3 is a three-pole circuit breaker comprising three compartments 10 disposed in side-by-side relationship. The center pole compartment (FIG. 1) is separated from the two outer pole compartments by insulating barrier walls formed with the housing base 9 and cover 11. The operating mechanism 13 is disposed in the center pole compartment and is a single operating mechanism for operating the contacts of all three pole units.

Each pole unit comprises a stationary contact 21 that is fixedly secured to a rigid main conductor 23 that in turn is secured to the base 9 by bolt 25. In each pole unit, a movable contact 27 is welded or brazed to a contact arm 29 that is mounted on a switch arm 31 by a pivot pin 33. The arms 29 and 31 for all three of the pole units are supported at one end thereof and rigidly connected on a common insulating tie bar 35 by which the arms of all three pole units move in unison. Each of the contact arms 29 is biased about the associated pivot pin 33 by means of a spring 37 to provide contact pressure in the closed position.

The operating mechanism 13 actuates the switch arms 31 between open and closed positions. The mechanism comprises a pivoted formed operating lever 39, a toggle comprising two toggle links 41 and 43, overcenter springs 45 and 47, and a pivoted releasable cradle or arm 49 controlled by the trip device 15. An insulating shield 51 for substantially closing an opening 53 in the cover 11, is mounted on the outer ends of the operating lever 39 and has an integral handle portion 55 extending out through the opening to enable manual operation of the breaker. The toggle links 41 and 43 are pivotally connected together by a knee pivot pin 57. The toggle link 41 is pivotally connected to the releasable arm 49 by a pin 59, and the toggle link 43 is pivotally connected to the switch arm 31 of the center pole unit by a pin 61. The overcenter springs 45 and 47 are connected under tension between the knee pivot pin 57 and the outer end of the operating lever 39. The circuit breaker is manually operated to the open position by movement of the handle portion 55 in a counterclockwise direction to the OFF position, which movement actuates the overcenter springs 45, 47 to collapse the toggle links 41 and 43 to the position shown in FIG. 1, and opening movement of the contact arm 29 for all of the pole units in a manner well known in the art.

The circuit breaker is manually closed by reverse movement of the handle portion 55 from the OFF position to the ON position, which movement causes the springs 45, 47 to move overcenter and straighten the toggle links 41, 43 thereby moving the contact arm 29, for all of the pole units, to the closed position as shown in broken line position.

The trip device 15 serves to effect automatic release of the releasable cradle or arm 49 and opening of the breaker contacts for all of the pole units, in response to predetermined overload conditions in the circuit breaker through any or all pole units of the circuit breaker, in a manner described hereinbelow.

The circuit through each pole unit extends from a right-hand terminal 63 through the conductor 23, the contacts 21, 27, the contact arm 29, a flexible conductor 65, that is secured to the contact arm 29, a conductor 67, a trip conductor 69, to a left-hand terminal connector 71. Bolt means 73 secure one end of the trip conductor 69 to the conductor 67 and the other end of the trip conductor 69 is disposed between a backup plate 75 and the terminal 71 where it is secured in place by mounting bolt 77 of the terminal 71.

As shown in FIGS. 2-6 the latch and trip device 15 comprises a molded insulating housing base 81 and a molded insulating housing cover 79 secured to the base to enclose a molded insulating trip bar 83 that is common to all three of the pole units. As shown in FIG. 3, the base 81 includes a pair of spaced partitions 85 and 87 which are vertically disposed and integral with the base for separating the interior of the housing into three compartments, each compartment containing one of the three poles. In a similar manner, the cover 79 is provided with partitions corresponding to partitions 85 and 87 and have mating surfaces therewith in a manner similar to the mating surfaces of the peripheral surfaces of the base 81 and cover 79 as indicated by a parting line 89 (FIG. 6).

As shown in FIG. 3, the partitions 85 and 87 have notches 91 and 93, respectively, which together with flat surfaces of the cover 79 serve as journals for round shaft portions 95 and 97 of the trip bar 83. Accordingly, when the housing base 81 and cover 79 are assembled they retain the trip bar 83 in place whereby the trip bar is free to rotate on an axis extending through the shaft portions 95 and 97. As shown more particularly, in FIG. 5, each section of the trip bar 83 located within the space compartments of the housing comprise upper and lower portions 83a and 83b, which are above and below the axis of rotation of the trip bar. Each upper portion 83a is provided with an adjusting screw and nut assembly 99 which cooperates with a bimetal member 101 for adjusting the spacing between the upper ends of the bimetal member and the trip bar portion 83a in response to the degree of deflection of the upper end of the member 101 toward the member 83a, whereby the trip bar 83 is rotated clockwise by the bimetal member and thereby trips the circuit breaker to the open position. The lower end portion 83b of the trip bar 83 is preferably provided with a drive screw 103 by which contact is made with an adjoining member for similar rotation of the trip bar in the manner to be described hereinbelow.

As shown more particularly in FIG. 5, the trip conductor 69 includes an inverted U-shaped intermediate portion 69a which constitutes a single loop of a stationary magnetic structure. Stationary magnetic structure also comprises a magnetic core 105, a U-shaped frame 107 having a pair of spaced flanges 109 one of which is shown in FIG. 5, and an armature 111. The assembly of the intermediate U-shaped portion 69a, the core 105, and the intermediate portion of the frame 107 together with the lower portion of the bimetal member 101 are secured in place by suitable means such as rivets 113 on the housing base 79. The lower end portion of the bimetal member 101 is in surface to surface contact with the conductor 69 whereby upon the occurrence of a low persistent overload current below a predetermined value of, for example, ten times normal rated current, the bimetal member 101 is heated and

deflects to the right through an air gap dependent upon the setting of the adjustment screw 99. Thus, when a low persistent overload current occurs, the trip bar 83 is actuated to trip the circuit breaker.

5 The armature 111 is disposed between the space flanges 109 of the U-shaped frame 107 and is pivotally mounted therein to rotate about an axis 115 near the lower end of the armature. For that purpose, the armature 111 is preferably mounted by suitable means such 10 as rivets 117 on a support lever 119 having oppositely extending out-turned lugs 121 which are seated in corresponding openings 123 in the flanges 109. Each flange 109 is also provided with a V-shaped notch 125 into which edge portions of the lever 119 and armature 111 extend. The notches 125 thereby limit movement of the assembly of the lever 119 and armature 111 when the armature is attracted toward the core 105. Accordingly, the assembly of the lever 119 and armature 111 which is biased in the clockwise direction by 15 coil springs 127 (FIG. 3) is movable counterclockwise against the springs to engage the drive screw 103 and thereby rotates the trip bar 83 clockwise. When an overload current above a value such, for example, as ten times normal rated current or a short circuit current occurs, the stationary magnetic structure is energized and the armature 111 is attracted toward the core 105 causing instantaneous release of the releasable arm 49 and opening of the contacts 21 and 27.

In addition to the foregoing, means are provided for 30 adjusting the spacing between the armature 111 and the core 105, whereby upon maximum spacing of the armature from the core, a greater current overload is required to attract the armature toward the core. Conversely, when the spacing is reduced, a smaller overload current is required to actuate the trip bar 83. For 35 that purpose a bracket 129 having a lower end disposed over the upper end of the lever 119 is mounted within the housing and is provided with calibration means including a calibration screw 131 at the upper end of the bracket 129. As shown in FIG. 3, each bracket 129 includes a notch 133 on each opposite side thereof which notch is seated in corresponding projections 135 of the housing base 79 where the brackets 129 are retained in place by the cover 81. An adjusting knob 137 is seated 40 within the top end of the housing base and is provided with a lower end portion having a cam surface. Inasmuch as the bracket 129 is biased counterclockwise about its pivot by the springs 127 of the lower lever 119 the calibration screw 131 rides on the cam surface of 45 a lower portion 139 of the adjusting knob 137.

As shown in FIGS. 3 and 5, each adjusting knob 137 includes a flange 141, the lower surface of which includes spaced notches 143. An index member 145 is disposed below the flange 141 and is provided with a projection 147 for engaging one of the spaced notches 143 as the calibrating screw 131 is rotated to the desired position. Accordingly, the desired spacing between the armature 111 and the core 105 is established 50 by rotation of the adjusting knob 137.

60 Since the housing cover 79 is used to hold the bracket 129 in place, it is necessary to assemble the trip unit completely before calibrating the position of the bracket 129. For that reason, a removable flexible shield 149 is disposed in an access opening 151 of the cover 79 in order to turn the calibrating screws 131 and 99. When the calibration is made, the shield 149 is replaced in the opening. The mechanism by which the re-

leasable arm 49 is released is shown in FIGS. 2, 4 and 6. The mechanism includes the trip bar 83, a trip lever 153 and a latch lever 155. A U-shaped mounting frame 157 is mounted on the base 81 with spaced upright sides 157a and 157b providing mounting support for the levers. The trip lever 153 includes a U-shaped portion 159 at the lower end which portion is mounted on a pivot pin 161 which extends from the side 157a of the frame. The U-shaped lower portion of the lever maintains the lever upright adjacent the frame side 157a. The upper end of the trip lever 153 includes a flange 163 which engages a notch 165 on the trip bar 83. As shown in FIG. 4 a portion of the trip bar extends through an opening 167 in the insulating base 79.

The latch lever 155 includes down-turned portions 155a and 155b which are mounted on a pivot pin 169 the opposite ends of which are secured in the sides 157a and 157b of the frame 157. A spring 171 is mounted on the pin 169 and has end portions engaging the levers 153 and 155 for biasing the levers in the latched positions. When the releasable arm 49 is in the latched position as shown in FIG. 1, the arm which is pivoted on a pivot pin 173 is secured in the latched position below the lever 155 and applies a rotatable force thereon. The latch lever 155 is prevented from turning due to engagement of the lower end of the lever on a pin 175 which is mounted in the U-shaped portion 159 of the trip lever 153. As a result of the rotating force on the latch lever 155, the trip lever 153 is biased clockwise and is prevented from movement by engagement of the flange 163 in the notch 165 of the trip bar 83. When the trip bar is rotated clockwise, the flange 163 is dislodged from the latch position within the notch 165 and the trip lever 153 rotates clockwise to move the pin 175 from engagement with the lower end of the latched lever 155, as a result the latch lever 155 is free to rotate about the pin 169 and thereby unlatch the releasable arm 49 from the latched position.

In accordance with this invention the circuit breaker 3 comprises means for manually tripping the breaker. The means includes a pushbutton or pin 177 which is disposed in a bore 179 of the adjusting knob 137. A compression spring 181 is provided in the bore 179 to hold the pin 177 in the non-trip or retracted position. As shown in FIG. 5 the lower end of the pin 177 has tapered or bevelled sides 183 and has a diameter greater than that of the pin. The upper end of the pin 177 has a cap 185 which is seated within an enlarged portion or recess 187 of the bore 179. In the retracted position the pin 177 is seated well within the recess 187 so that no accidental tripping is possible. To trip the circuit breaker the pin 177 is depressed by inserting a small screwdriver, or other small tool, into the recess. Moreover, the adjusting knob 137 may be rotated without affecting the position of the pin.

In addition to the pin 177 the manual tripping means

comprises an inclined surface 189 at the upper edge of the trip bar 83 aligned with the inclined surface 189. Upon depression of the pin 177 the conical or tapered side 183 engages the inclined surface 189 and rotates the trip bar 83 clockwise (FIG. 5) to trip the circuit breaker 3 as described above. Although the pin 177 and the trip bar 83 are both disclosed as having inclined or bevelled surfaces, it is understood that the device would be operable if one of the trip bar and pin were provided with inclined or bevelled surfaces.

Accordingly, the device of the present invention provides a new and novel trip device for a circuit breaker which is of a more compact size than the previous trip devices of the same rating.

What is claimed is:

1. A circuit interrupter trip device comprising a circuit breaker having a first insulating housing, a circuit breaker mechanism within the housing and comprising separable contacts adapted to be connected as part of 15 the distribution system, the circuit breaker mechanism comprising a releasable member movable when released from a latched position to effect opening of the contacts, a stationary magnetic structure for each conductor of the distribution system and comprising a coil 20 and core assembly and an armature, a trip bar movable to a tripped position to effect release of the releasable member and being biased in the latched position, the housing having an opening therein, an adjusting knob accessible at the opening and being manually operable 25 to adjust the trip characteristics of the trip means, the adjusting knob having a bore therethrough, a trip pin accessible at the bore and being manually movable between retracted and depressed positions with the trip bar, and the trip pin being biased in the retracted position 30 and being movable to the depressed position to move said trip bar to the tripped position.

2. The circuit interrupter trip device of claim 1 in which the magnetic structure and the trip bar are mounted within a second insulating housing, and the 40 second insulating housing being mounted within the first insulating housing.

3. The circuit interrupter trip device of claim 2 in which the manually operable trip pin extends through the second insulating housing.

4. The circuit interrupter trip device of claim 3 in which at least one of the end portions of the trip pin and the edge surface of the trip bar is tapered.

5. The circuit interrupter trip device of claim 4 in which the end portion of the trip pin is tapered and 50 aligned with an edge of the trip bar.

6. The circuit interrupter trip device of claim 5 in which the edge surface of the trip bar is bevelled and aligned with the tapered end portion of the trip pin.

7. The circuit interrupter trip device of claim 6 in 55 which the trip pin and trip bar are aligned.
